A cross-sectional diagram of a mechanical assembly. It features a central vertical bore labeled with the number '7'. This bore is surrounded by a thick, hatched cylindrical wall. Above this wall, there is a horizontal flange or plate. The top edge of this flange is notched or stepped, with a small protrusion on the left side. The overall structure is rectangular in plan view, with the central bore being the primary vertical axis.

CHUSETTS.

SHUTTLE CHECK AND LOCK FOR LOOMS.

No. 820,589.

Specification of Letters Patent.

Patented May 15, 1906.

Application filed July 18, 1904. Serial No. 217,010.

To all whom it may concern:

Be it known that I, FRANCIS ARTHUR MILLS, a citizen of the United States, residing at Lawrence, in the county of Essex and State of Massachusetts, have invented certain new and useful Improvements in Shuttle Checks and Locks for Looms; and I do hereby declare the following to be a full, clear, and exact description of the invention, such as will enable others skilled in the art to which it appertains to make and use the same.

The invention in looms which forms the subject of this patent is directed to the provision of a lever device having a yielding actuating function upon a shuttle-binder whereby the shuttle's direct impact upon said lever device causes said lever device to yieldingly press upon said binder to check and lock the movement of said shuttle, and thereby prevent rebounding of the shuttle.

The following description, read in connection with the accompanying drawings, will enable any person skilled in the art to which my invention relates to understand its nature and to practice it in the form in which I prefer to employ it; but it will be understood that my invention is not limited to the precise form, construction, and arrangement of the parts herein illustrated and described, as various changes and modifications may be made in the lever device and its coöperating parts whereby the binder-actuating lever device is caused to have a yielding pressing function upon a binder and the binder on the shuttle by the impact of a side of the shuttle upon the lever device. In coöperation with the yielding function of the binder-actuating lever device the shuttle-binder is provided with yielding means whereby the shuttle is frictionally checked and locked by and under a yielding pressure.

Referring to the drawings, Figure 1 is a top plan view of the left end of a loom-lay and shuttle-box thereon and with one embodiment of my invention applied thereto, the cap-plate or shuttle-guide being removed, the shuttle shown in the position just entering the shuttle-box and the yielding binder-actuating lever device in its normal position.

Fig. 2 is a similar view showing the shuttle having fully entered the shuttle-box and having operated the yielding lever device upon

the binder and the yielding binder upon the shuttle to lock the shuttle at the end of its movement in the box, the binder being broken away to show the lever device and its engagement with the shuttle. Fig. 3 is a back view of the same, the pivot-mounting of the shuttle-binder and of its actuating-lever device being shown in section. Fig. 4 is a transverse section taken on the line *a b* of Fig. 2, showing the yielding lever device in the position in which it locks the shuttle and showing the contact-face of said device with the shuttle. Fig. 5 shows in section the eccentric for adjusting the lever 20.

Each end of the loom-lay 1 is provided with my improved shuttle-lock and has the shuttle-box thereon, the front wall 2, the cap-plate 3, the back wall 4, and the picker 5, the picker-stick 6 whereof is adapted to move in a slot 7 in the shuttle-box to actuate the shuttle 8, and the protector-shaft 9, its controlling spring 10, and its standing binder-finger 11 may be and are all of the well-known construction.

The binder 12 is fulcrumed at its outer end on the lay by a bolt 13 and has the usual swell 14 to receive the ingoing shuttle, while at its inner end the binder is caused to rest against the box-wall 4 when the box is empty by the pressure of the protector-finger, as in Fig. 1. The binder is fulcrumed at its outer end on a bolt 13, and its inner wall is provided with a facing 15 of yielding substance for causing a yielding binding function upon the shuttle and which is supplemented by a wear-facing, preferably of leather, 16 to protect the yielding substance and provide a smooth wear-surface.

For actuating the binder upon the shuttle I employ a lever device having a yielding function, and to obtain the required pressing force on the binder I prefer to construct the lever device of a plurality of yielding members, one of which, 17, has its fulcrum on the fulcrum-bolt of the binder and is constructed and arranged to be engaged and operated to separately engage the shuttle and the binder by the ingoing shuttle and actuate the binder with a yielding pressure against the shuttle. For this purpose the primary lever member 17 at its fulcrumed end is fitted within a recess, Fig. 3, on the under side of the binder and has a binder

part 18 rising in a recess at the inner wall of the binder and provided with a wear-facing 19, preferably of leather. As shown in Fig. 4 and by dotted lines in Fig. 3, that part 18 of the lever member 17 which receives the impact of the ingoing shuttle presents a bearing-surface to the whole width of the shuttle, and thereby causes its wear-facing to have an effective binding action upon the shuttle. 5
10 The free end of this lever 17 rises at a point about the middle of the width of the binder and engages the meeting end of the coacting lever member 20, which being pivoted meditately of its length is caused to be yieldingly pressed against the inner end of the binder by the impact of the shuttle against the primary lever member 17, which in turn forces the coacting member 20 against the shuttle-binder, whereby the shuttle is frictionally 15 checked and locked. To render such action effective and satisfactory, I cushion the action of the binder upon the shuttle and the action of the yielding device upon the binder, and for this purpose the meeting ends of the 20 lever members are provided with a yielding bearing 21, while the shuttle-binder is provided with a yielding bearing 22 for the lever device. As seen in Fig. 1, the lever device is maintained in its normal position by a blade-spring 23, attached to the binder, which 25 serves to cause a yielding pressure of the binder upon the shuttle when operated by the lever device, and it also exerts a constant outward force upon the lever device, causing 30 their meeting ends to maintain contact, and thereby causing the impact-lever to be maintained in the path of the shuttle to receive and deliver the impact of the shuttle upon the yielding lever device and the latter upon 35 the binder to check and lock the shuttle under a yielding function, it being understood that the picker-stick moves back and forth free of the impact part of the binder-actuating lever device. The blade-spring also aids 40 to cushion the impact of said lever device upon the shuttle-binder and the latter upon the shuttle. The shoulder of the shuttle on entering the box strikes the swell of the binder, forcing its free end outward against 45 the corresponding end of the lever device, which is thereby caused to force the impact-lever part into the path of the shuttle, the impact of which forces said impact-lever part outward, causing thereby the lever device to 50 be forced inward against the shuttle-binder and force it against the shuttle. In this action the lever impact part is cushioned upon the shuttle, the lever device is cushioned upon the shuttle-binder, and the latter is 55 cushioned upon the shuttle, so that both the lever device and the binder are yieldingly pressed against the shuttle to check and lock it with yielding pressure when at the moment that the shuttle is picked the binder- 60 actuator lever device is released, which re-

leases the binder pressure. In this operation the free end of the binder engages the protection-finger and by its spring-pressure helps the checking of the shuttle.

It is important to note that while the lever device is caused to act with a yielding, checking, and locking function upon the shuttle the lever device is caused to act with a compound leverage pressure, the effect of which is to more certainly check and stop the shuttle, because the compound lever device gives increased leverage and renders the lever members sensitive and active in transmitting the pressure of the impact of the shuttle upon the lever device. 70 75 80

I prefer to provide a leather facing for the lever impact part and a like leather wear-facing 24 for the inner wall of the shuttle-box, against which the shuttle is pressed in the operation of checking and locking it. 85

I prefer to fulcrum the shuttle-binder and the impact member 17 of the lever device on the same bolt, as it gives a compact arrangement of these parts and a swing movement from the same center. It is also of advantage 90 to place the impact part meditately of the length of the primary lever member, because it thereby allows sufficient movement of the shuttle against the impact part to give the latter its full locking effect of the shuttle-binder upon the shuttle at the time the latter strikes the picker, and to obtain the best results from this effect I have arranged cushions on the ends of the lever device and also between it and the binder. In using the 95 bolt as a fulcrum common to both the shuttle-binder and the primary lever a bushing 25 is provided for the shuttle-binder bolt, and a separate bushing 26 is provided for said lever, as in Fig. 3. 100 105

Referring to the lever device, it will be noted that its member 20 is mounted loosely upon an eccentric pin or stud 27, Fig. 5, which is clamped in a boss 30, fixed to a plate 28, which is secured to the rear side of the lay by bolts 29, which pass through slots in said plate to provide for its adjustment. The eccentric stud is clamped by a shoulder 31 upon the boss by a nut 32 at the under side of the boss, and thereby provides a 110 means for adjusting the said lever member fulcrum outward or inward for the purpose of causing it to give more or less yielding pressure upon the binder and the latter upon the shuttle. This adjustment also serves to 115 compensate for wear of the parts of the said lever device. The adjustment of the plate 28 is to allow the binder-actuated end of lever member 20 to be set so as to act against the binder nearer to or farther from the protection-finger, and thereby allow the lever device to be put on looms in which the protection-finger may be positioned to act upon the binder at its end or away from its end, as 120 125 130 might be and often is in different looms.

The adjustment of the lever member is made by loosening the nut 32 and turning the eccentric stud to the right or to the left, and thereby causing one of its ends to be moved nearer to or farther away from the end of the binder and its other end correspondingly moved in its relation to the other lever member 17, and in this way the impact of the shuttle upon the face of said lever member 17 causes it to be pressed with more or less force against the shuttle-binder, as may be found to give the best results in checking and locking the shuttle. The adjustment of the plate therefore is to position the lever device horizontally to suit the position of the protection-finger, while the adjustment of the lever device laterally upon said plate is to cause it to be pressed with more or less force against the shuttle-binder.

20 I claim—

1. In a loom, the lay, the shuttle-box having a shuttle-binder, the shuttle and picking mechanism therefor, a binder-actuating lever device having a shuttle impact-face in the path of and operated by a side of the shuttle, and another part of said device operating on a movable part of the shuttle-binder, and yielding means located between the shuttle impact-face of said device and the impact part of said device on the shuttle-binder for causing said binder to be yieldingly pressed on the shuttle at or near the limit of its travel in the shuttle-box and throughout the remaining extent of its travel in the box.

2. In a loom, the lay, the shuttle-box having a shuttle-binder, the shuttle and picking mechanism therefor, a binder-actuating lever device having a shuttle impact-face in the path of and operated by a side of the shuttle, and another part of said device operating on the shuttle-binder, said lever device and said binder each having yielding contacts, and said binder having a flexible impact-face to coact with said yielding contacts for causing the shuttle to be yieldingly checked and locked by a yielding pressure in the shuttle-box by the impact of the shuttle upon said device.

3. In a loom, the lay, the shuttle-box, the shuttle-binder, the shuttle and picking mechanism therefor, a binder-actuating lever device composed of coacting lever members, including cushioning contacts for the shuttle and for the binder, located between the meeting ends of the lever members and between one of said lever members and the movable end of the shuttle-binder.

4. In a loom, the lay, the shuttle-box having a shuttle-binder, the shuttle and picking mechanism therefor, a binder-actuating lever device, having a shuttle impact-face in the path of and operated by a side of the shuttle, and another portion of said device operating on said binder, and both said lever device and said binder having yielding means lo-

cated between the shuttle-impact face of said device and the shuttle-impact face of said binder, for causing both said lever device and said binder to yieldingly press upon the shuttle by the impact of said shuttle on said lever device.

5. In a loom, the lay, the shuttle-box, the shuttle-binder, the shuttle and picking mechanism therefor, a binder-actuating lever device including yielding contacts for the shuttle and for the binder, said yielding contacts being located outside of the binder, and a blade-spring connected to the binder, and with said lever device.

6. In a loom, the lay, the shuttle-box having a shuttle-binder, the shuttle and picking mechanism therefor, a binder-actuating lever device, having a shuttle impact-face in the path of and operated by a side of the shuttle, and another portion of said device operating on the shuttle-binder, the said lever device and said binder, each having yielding means for causing both said lever device and said binder to be yieldingly pressed on the shuttle by the impact of the shuttle on said lever device.

7. In a loom, the lay, the shuttle-box, a shuttle-binder, the shuttle and picking mechanism therefor, a binder-actuating lever device having a shuttle impact-face in the path of and operated by a side of the shuttle, and having a connection with a movable part of said shuttle-binder, and said binder having a flexible impact-face for the shuttle and means for causing said device to press said binder on the shuttle by the impact of the shuttle on said device.

8. In a loom, the lay, the shuttle-box having a pivoted shuttle-binder, the shuttle and picking mechanism therefor, a binder-actuating lever device having an impact-face in the path of and operated by a side of the shuttle, and said device having a yielding connection with the free end of the shuttle-binder, and said binder having a flexible impact-face adapted to yield upon the shuttle for the purpose stated.

9. In a loom, the lay, the shuttle-box, the shuttle-binder, the shuttle and picking mechanism therefor, a binding actuating-lever device composed of coacting lever members, including yielding contacts for said shuttle and for said binder, one of said lever members having its fulcrum in common with the fulcrum of said binder.

10. In a loom, the lay, the shuttle-box having a shuttle-binder and a protector device operated by said binder, the shuttle and picking mechanism therefor, a frictional shuttle-lock comprising lever members, one of which is spring-pressed on said binder and yieldingly connected to another, having a shuttle impact-face in the path of and operated by a side of the shuttle, for causing said binder to be yieldingly pressed on the shuttle by the

impact of a side of the shuttle on said lever device.

11. In a loom, the lay, the shuttle-box having a shuttle-binder, the shuttle and picking mechanism therefor, a lever device having an impact-face in the path of and operated by a side of the shuttle, and having a yielding connection with said shuttle-binder and protector mechanism operated by said binder, and means independent of said protector mechanism and operated by said lever device for causing said binder to be yieldingly pressed on the shuttle throughout the remaining portion of its travel in the box, and operated by the impact of a side of the shuttle directly on said device.

12. In a loom, the lay, the shuttle-box, the shuttle and picking mechanism therefor, a shuttle-binder pivotally mounted at or near the outer end of the lay and protector mechanism operated by said binder, and means for causing said binder to be yieldingly pressed on the shuttle by the impact of a side of the shuttle on said means throughout the remaining portion of the travel of the shuttle in the box.

13. In a loom, the lay, the shuttle-box, the shuttle and picking mechanism therefor, and a shuttle-binder, a binder-actuating lever device having yielding means acting between the impact of said shuttle upon said lever device and the impact of said lever device upon said shuttle-binder, and means for adjusting said lever device laterally to cause it to act with more or less pressure upon the binder to check and lock the shuttle.

14. In a loom, the lay, the shuttle-box having a shuttle-binder, the shuttle and picking mechanism therefor, a binder-actuating lever device having a shuttle impact-face in the path of and operated by a side of the shuttle, and another portion of said device operating on a shuttle-binder, and said device having yielding means acting between the shuttle impact-face of said device and the impact of said device upon said binder, and an adjustable eccentric fulcrum on which said binder-lever is loosely mounted, for causing more or less yielding pressure of the binder on the shuttle by the impact of the shuttle upon said lever device.

15. In a loom, the lay, the shuttle-box having a shuttle-binder, the shuttle and picking mechanism therefor, a binder-actuating lever device composed of coacting lever members, including yielding contacts for the shuttle and for said binder, and an adjustable eccentric fulcrum on which said binder-lever member is loosely mounted for the purpose stated.

16. In a loom, the lay, a shuttle-box thereon, a shuttle-binder, the shuttle and picking mechanism therefor, a binder-actuating lever device composed of coacting members including yielding contacts for said shuttle and

for said binder, one of said lever members mounted upon an adjustable eccentric fulcrum, the other of said lever members having its fulcrum in common with the fulcrum of said binder.

17. In a loom, the lay, the shuttle-box thereon, the shuttle and picking mechanism therefor, and a shuttle-binder, a binder-actuating lever device of coacting members, one of said lever members mounted upon a laterally-adjustable fulcrum, a plate supporting said adjustable lever member, and means for adjusting said plate for the purpose stated.

18. In a loom, the lay, the shuttle-box thereon, a shuttle-binder, the shuttle and picking mechanism therefor, a binder-actuating lever device of coacting members, a plate supporting one of said lever members, means for adjusting said plate with its lever member horizontally, and means for adjusting said lever member laterally on said plate.

19. In a loom, the lay, the shuttle-box, the shuttle and picking mechanism therefor, a shuttle-binder pivotally mounted on the lay and protector mechanism operated by said binder, and means for yieldingly pressing said binder upon said shuttle, operated by the impact of a side of the shuttle upon said means for yieldingly checking and locking the shuttle in the shuttle-box.

20. In a loom, the lay, the shuttle-box having a shuttle-binder, the shuttle and picking mechanism therefor, a binder-actuating lever device having a shuttle impact-face in the path of and operated by a side of the shuttle, and another portion of said device operating on a shuttle-binder, and said device having rubber contacts located between the shuttle impact-face of said device and the shuttle impact-face of said binder, for yieldingly checking and locking the shuttle in the shuttle-box by the impact of the shuttle upon said device.

21. In a loom, the lay, the shuttle-box having a shuttle-binder, the shuttle and picking mechanism therefor, a binder-actuating lever device having a shuttle impact-face in the path of and operated by a side of the shuttle, and said device having a connection with the shuttle-binder, the said lever device and the said binder each having rubber contacts for causing the shuttle to be yieldingly checked and locked in the shuttle-box by the impact of the shuttle upon said device.

22. In a loom, a lay, a shuttle-box, a shuttle-binder, the shuttle and picking mechanism therefor, a binder-actuating lever device comprising a pair of coacting lever members, one of said lever members acting with a yielding impact upon the shuttle, and the other acting with a yielding impact on the shuttle-binder to cause the binder to yieldingly press on the shuttle.

23. In a loom, the lay, the shuttle-box, the shuttle-binder, the shuttle and picking mechanism therefor, a binder-actuating lever de-

vice comprising coacting lever members, one of said lever members having an impact-face acting upon the shuttle at the inner side of said binder, and the other lever member delivering a yielding impact upon the outer side of said binder, both said lever members meeting with a yielding contact.

24. In a loom, the lay, the shuttle-box, the shuttle and picking mechanism therefor, a binder-actuating lever device comprising coacting lever members one of which has an impact-face yieldingly acting upon the shuttle, and means at the end of the other lever member for delivering a yielding impact on the binder, and a yielding impact facing on the shuttle-binder.

25. In a loom, the lay, the shuttle-box, a pivotally-mounted shuttle-binder, the shuttle and picking mechanism therefor, a binder-actuating lever device comprising coacting lever members, one having an impact-face adjacent the pivoted end of said binder, and a yielding contact at its other end, the other of said levers engaging a yielding contact upon the free end of said shuttle-binder, and yielding contacts at the meeting ends of said lever members.

26. In a loom, the lay, the shuttle-box, the shuttle and picking mechanism therefor, a pivotally-mounted shuttle-binder having a yielding impact-face for the shuttle and an external yielding contact at its free end, a binder-actuating lever device comprising co-

acting members, one of which has a shuttle impact-face and a yielding contact connecting it with the binder-actuating lever, the binder and the shuttle-lever member mounted upon the same fulcrum.

27. In a loom, the lay, the shuttle-box, the shuttle-binder, the shuttle and picking mechanism therefor, a binder-actuating lever device comprising coacting lever members, and a plurality of contacts whereby said lever members are caused to apply a yielding pressure to check and stop the shuttle, one of said contacts acting upon the shuttle within the box, and the other of said contacts acting upon the back of the binder with a yielding pressure.

28. In a loom, the lay, the shuttle-box, the shuttle and picking mechanism therefor, a shuttle-binder pivotally mounted on the lay, a protector device operated by said binder, a lever device having a shuttle impact-face in the path of and operated by a side of the shuttle, and means external to the binder for yieldingly pressing said binder upon the shuttle during the remaining portion of its travel in the box.

In testimony whereof I have signed my name to this specification in the presence of two subscribing witnesses.

FRANCIS ARTHUR MILLS.
